United States Patent [19]

Umemoto et al.

[11] Patent Number: Des. 307,398

[45] Date of Patent: ** Apr. 24, 1990

[54] **ATOMIC ABSORPTION
SPECTROPHOTOMETER**

[75] Inventors: Shouji Umemoto, Kodaira; Masamichi Tsukada, Ibaragi; Masatoshi Kitagawa, Mito, all of Japan

[73] Assignee: Hitachi, Ltd., Tokyo, Japan

[**] Term: 14 Years

[21] Appl. No.: 70,536

[22] Filed: Jul. 7, 1987

[30] Foreign Application Priority Data

Jan. 7, 1987 [JP] Japan 62-37

[52] U.S. Cl. D10/46

[58] Field of Search D10/46; D24/1.1; 356/319, 326, 325; 250/428

[57] CLAIM

The ornamental design for a atomic absorption spectrophotometer, as shown.

DESCRIPTION

FIG. 1 is a front, top and left side perspective view of a atomic absorption spectrophotometer showing our new design;

FIG. 2 is front elevational view thereof;

FIG. 3 is a right side elevational view thereof;

FIG. 4 is a top plan view thereof;

FIG. 5 is a bottom plan view thereof;

FIG. 6 is a left side elevational view thereof; and

FIG. 7 is a rear elevational view thereof.

FIG. 1

FIG. 2

FIG. 3

FIG. 4

FIG. 5

FIG. 6

FIG. 7
